(57) **CLAIM**

The ornamental design for a French press, as shown and described.

DESCRIPTION

FIG. 1 is a front, left side perspective view of a French press showing our new design;

FIG. 2 is a rear, right side perspective view of FIG. 1;

FIG. 3 is a front elevation view of FIG. 1;

FIG. 4 is a rear elevation view of FIG. 1;

FIG. 5 is a left side elevation view of FIG. 1;

FIG. 6 is a right side elevation view of FIG. 1;

FIG. 7 is a top plan view of FIG. 1; and,

FIG. 8 is a bottom plan view of FIG. 1.

The broken lines in the drawings depict portions of the French press that form no part of the claimed design. The stippling depicts the contrast in surfaces, as shown.
